UNITED STATES PATENT OFFICE

162,980

STOVE BACKGUARD

Daniel P. O'Keefe, Los Angeles, Calif.

Application March 8, 1950, Serial No. 8,396

Term of patent 14 years

(Cl. D81—25)

To all whom it may concern:

Be it known that I, Daniel P. O'Keefe, a citizen of the United States, residing at Los Angeles, in the county of Los Angeles and State of California, have invented a new, original, and ornamental Design for a Stove Backguard, of which the following is a specification, reference being had to the accompanying drawings, forming a part thereof.

Fig. 1 is a perspective view of a stove backguard, showing my new design, showing the front, top and one end; Fig. 2 is a top plan view thereof; and Fig. 3 is an elevational view of the end opposite that shown in Fig. 1.

I claim:

The ornamental design for a stove backguard, as shown.

DANIEL P. O'KEEFE.
